UNITED STATES PATENT OFFICE.

WILLIAM G. CRUMLISH AND WALTER F. SCOTT, OF WILMINGTON, DELAWARE.

DESIGN FOR A RADIOCABINET.

Application filed March 9, 1925. Serial No. 12,659. Term of patent 3½ years.

To all whom it may concern:

Be it known that we, WILLIAM G. CRUMLISH and WALTER F. SCOTT, citizens of the United States, residing in Wilmington, county of New Castle, State of Delaware, have invented a new, original, and ornamental Design for Radiocabinet, of which the following is a specification, reference being had to the accompanying drawing, forming

ing part thereof, in which the single figure of the drawing is a perspective view of a radiocabinet embodying our new design.

We claim:

The ornamental design for a radiocabinet, as shown.

WILLIAM G. CRUMLISH.
WALTER F. SCOTT.
